UNITED STATES PATENT OFFICE.

FRANK L. O. WADSWORTH, OF WILLIAMS BAY, WISCONSIN, ASSIGNOR, BY
MESNE ASSIGNMENTS, TO PRESSED PRISM PLATE GLASS COMPANY, A
CORPORATION OF WEST VIRGINIA.

REFLECTING-PANEL.

SPECIFICATION forming part of Letters Patent No. 737,178, dated August 25, 1903.

Application filed March 30, 1898. Serial No. 675,796. (No model.)

To all whom it may concern:

Be it known that I, FRANK L. O. WADSWORTH, a citizen of the United States, residing at Williams Bay, in the county of Walworth and State of Wisconsin, have invented 5 certain new and useful Improvements in Reflecting-Panels, of which the following is a specification.

My invention has for its object to provide 10 a ready, inexpensive, and efficient means of more fully and uniformly lighting dark rooms; and to this end my invention consists of a portable panel of the same general size and shape as the ordinary window sash or panel 15 provided with a series of reflectors secured, as fully set forth hereinafter, and as illustrated in the accompanying drawings, in which—

Figure 1 is a face view of a reflecting-panel 20 embodying my invention. Fig. 2 is a part transverse section.

The panel consists, generally speaking, of a frame, two sheets of glass, and a series of 25 flexible reflector-plates. The panel A is of a shape and character to suit the particular 30 situation of its use; but for general purposes it is rectangular and adapted to be placed in position within or without the pane of a window or window-sash and having glass front 35 and back sides B B, parallel to each other, fitted to the frame as closely as possible at the edges and preferably sealed therein, so as to exclude dust, air, and moisture from the intermediate space. The reflector-plates 40 are total reflectors on both surfaces of polished metal. The frame supporting the strips 45 and the protecting-plate B B may be of wood of the construction shown, and the ends of the plates may be secured between flanged strips 7 7, screwed to the side of the frame, or may be turned up to form ears 8, punctured for the passage of the securing-screws which draw the ends of the strips toward the 50 sides of the case, and thereby stretch the strips taut and tend to prevent sagging. I have found in the practical manufacture of

such structures that the draft upon the securing-screws often, instead of straightening the strips, bends in the sides of the frame, but that this is prevented by inserting first 50 the pane B, which, as before stated, is fitted as closely as possible against the sides of the frame and which by its lateral rigidity prevents the latter from bending inward. To further prevent sagging where the reflection- 55 plates are long, they may be supported between their ends by longitudinal strips 9, which may be strips of metal or glass set edgewise to present as little surface as possible to the light, or, as shown, of rods, each extending through holes in the plates, with enlargements 10 for the latter to rest upon.

The prevention of the sagging of reflection- 60 strips is of great importance, inasmuch as if the strips lose their alignment the light-rays 65 are concentrated or dispersed instead of being directed as intended by the adjustment of the structure.

By thus forming the illuminator in the 70 form of a panel it may be sold as an article complete in itself ready for immediate application in any position desired, and especially in place of the usual glazed sash, for when constructed as above it serves not only the purpose of an illuminating structure, but also 75 in place of a storm-sash, the usual glass being sometimes removed.

Without limiting myself to the precise construction shown, I claim—

A reflector-panel consisting of a frame, a 80 series of flexible reflector-strips within the frame, means for stretching the strips longitudinally and a pane B fitting within the frame, substantially as and for the purpose set forth. 85

In testimony whereof I have signed my name to this specification in the presence of two subscribing witnesses.

F. L. O. WADSWORTH.
